(57) **CLAIM**

The ornamental design for a fish measuring device, as shown and described.

DESCRIPTION

FIG. 1 is a front elevation view of the fish measuring device showing my new design.

FIG. 2 is a side view of the design of FIG. 1.

FIG. 3 is a top view of the design of FIG. 1.

FIG. 4 is an end view of the design of FIG. 1.

FIG. 5 is an end view of the design of FIG. 1 opposite the end view of FIG. 4.

FIG. 6 is a side view of the design of FIG. 1 opposite the side view of FIG. 2; and,

FIG. 7 is a bottom view of the design of FIG. 1.
